(57) **CLAIM**

The ornamental design for the television conference system with displays, as shown and described.

DESCRIPTION

FIG. 1 is a front elevational view of the television conference system with displays showing our new design;

FIG. 2 is a rear elevational view thereof;

FIG. 3 is a side elevational view of one side thereof;

FIG. 4 is a side elevational view of the other side thereof;

FIG. 5 is a top plan view thereof;

FIG. 6 is a bottom plan view thereof;

FIG. 7 is a perspective view thereof;

FIG. 8 is a perspective view like FIG. 7 but with panels inclined with respect to the vertical;

FIG. 9 is a view like FIG. 4 but with all panels aligned;

FIG. 10 is a scaled-down perspective view with all panels aligned; and,

FIG. 11 is a scaled-down perspective view with all panels aligned and inclined with respect to the vertical.
